(57) **CLAIM**

The ornamental design for a spraying device for bottles, as shown and described.

DESCRIPTION

1. Spraying device for bottles

1.1 : Perspective

1.2 : Left

1.3 : Top

1.4 : Front

1.5 : Right

1.6 : Back

1.7 : Bottom

The broken lines shown are included for the purpose of illustrating portions of the spraying device for bottles that form no part of the claim.
